REUSABLE BOTTLE STOPPER WITH SEVERABLE SKIRT PORTION Leszek Woydatt and Rodolphe Chwialkowski,
Paris, France

Application October 26, 1951, Serial No. 253,286

Claims priority, application France October 27, 1950

1 Claim. (Cl. 215—41)

The present invention refers to a closure or stopper structure for mineral water bottles and other containers, which is placed on the bottle before the latter is distributed on the market; said closure structure being torn off at the first opening of the bottle, leaving a cap comprising means for placing said cap an indefinite number of times on the neck of the bottle for closing the same, the removal of a torn-off part, at the time of the first opening of the bottle, affording however the further use of said bottle due to the fact that it can be closed again with the remaining part of the closure structure.

It is, therefore, one of the primary objects of the invention to provide means ensuring firm and safe closing of bottles and continued use of a removable cap on the bottle after destruction of an essential part of the bottle closure device.

It is another important feature of the invention to provide means facilitating the manufacture of inexpensive bottle closure means fulfilling the dual purpose of strong and durable closure for the bottle and of incorporating in said closure a bottle cap, which may be separately used, after the closure has been partly destroyed for obtaining access to the bottle neck.

These and other objects of the invention will become further apparent from the following detailed description, reference being made to the accompanying drawings, showing preferred embodiments of the invention.

Figure 1 is a sectional elevation of one embodiment of the stoppering device according to the present invention.

Figure 2 is an elevation of the neck of a bottle completely closed by means of the stoppering device of Fig. 1.

Figure 3 is a lateral elevation of a second embodiment of the stoppering device.

Referring now more particularly to Fig. 1, the stoppering or closure device consists of a capsule or cap portion 11 having a base 11a and a side wall 11b, the latter being thinner adjacent its junction with the base than at its edge 12 remote from the base. The closure device further includes a skirt portion 13 having a central section 13a of substantially uniform wall thickness, a first edge section 15 of lesser wall thickness, and a second edge section 14 of greater wall thickness than said central section. The edge section 15 is joined to the edge 12 of the side wall 11b and thus constitutes, together with the remainder of the skirt portion 13, a prolongation of the side wall 11b. A hollow, substantially cylindrical member 16 protrudes from the base 11a and is disposed interiorly of and concentrically with the side wall 11b and skirt portion 13. The member 16 extends to a location beyond the junction between the side wall edge 12 and the first or thin edge section 15 of the skirt portion 13 and is designed to fit into the neck of the bottle which is closed by means of this stoppering device. The stoppering device comprises a lug or thumb piece 17, protruding beyond its periphery and its lower portion or pressure surface 18 is essentially directed toward the second edge section 14 of the skirt portion 13 to

2

allow a better grasp when opening the bottle and when removing therefrom this stoppering device.

In Fig. 2, the neck 19 of a bottle is terminated, at its upper portion, by a marginal rim 20 below which is placed a frusto-conical portion 21; 22 designates a groove or constricted area connecting the frusto-conical portion 21 with the neck 19 of the bottle.

The stoppering device is engaged on the neck 19 of the bottle by means of the annular groove formed between the outer surface of the cylindrical member 16 on the one hand and the inner surface of the side wall 11b and skirt portion 13 on the other hand in such a manner that the edge or collar 12 of the side wall 11b placed underneath the marginal rim 20 of the neck of the bottle and that the skirt portion 13 surrounds the frusto-conical portion 21. The edge section 14 is thus placed in abutting engagement with the shoulder formed by the groove 22 while the cylindrical sleeve or member 16 is housed inside the neck of the bottle.

When it is desired to open the bottle closed by this stoppering device, a pressure is exerted on the pressure surface 18 of the lug 17, in the direction of the arrow F₁ (Fig. 2). This motion tends to remove the assembly of the stoppering device from the neck of the bottle, but since the lower collar or edge section 14, of the skirt portion 13, is placed below the shoulder of the neck, it prevents the skirt portion 13 from sliding along the frusto-conical portion 21 of the neck. The region of lowest resistance 15, which is weaker than either the skirt portion of the cap portion, is ruptured and the cap portion 11 of the stoppering device is severed or freed from the skirt portion 13 and can thus be removed from the marginal rim 20 of the neck 19 of the bottle.

When it is desired to close the bottle again, the cap or capsule is placed back on the neck of the bottle, the collar 12 again being placed on the marginal rim 20 of the neck 19 of the bottle. Similarly, the sleeve 16 enters the neck.

In Fig. 3, the central skirt section 23 connecting the capsule 24 with the lower collar or edge section 25 consists of a number of tongues formed by the provision of a plurality of substantially parallel slots 26a. A region of lowest tear resistance is constituted by a thin edge section 27. The slots 26a render the tongues 26 more flexible and facilitate adaptability of the skirt portion to the neck of the bottle, the tongues being torn off at the first opening.

The stoppering device may be made of a plastic material such as rubber, natural or synthetic, of resilient material unaffected by the chemical agents involved, particularly of a synthetic resin such as polystyrene. It may be transparent, translucent or of any suitable color.

This stoppering device may bear designs, emblems and markings. It may be given any outside shape, pleasing and attractive for sales purposes.

The stoppering device according to the invention ensures a perfect sealing due to the engaging of the inner sleeve 16 in the bottle, the clamping of the edge 12 of the side wall 11b under the marginal rim of the bottle and the application of the skirt along the neck thereof. In addition, the contents of the bottle may not be tampered with as long as it has not yet been delivered for consumption, since, from its first opening, the skirt 13 or 23 becomes separated from the capsule, thus testifying to this first opening. Finally, the capsule which remains after the separation of the skirt, still makes it possible to stopper the bottle in a perfectly tight manner as many times as desired, which avoids the escape of gases or the contact of the liquid contained inside the bottle with the atmosphere. The skirt might be glued or made to adhere to the glass of the bottle by any other means, for instance by heating the lower portion of the

skirt, to aid in the tearing off operation and to contribute to the tamper proofing characteristics of the closure device.

It can thus be seen that there has been provided according to the invention a unitary closure device for bottles and like containers comprising a cap portion having a relatively thick wall, said cap portion being provided with an outwardly projecting lug for manipulation of said cap portion and being provided with an inner annular groove for engagement with the rimmed end of the neck of a bottle, a relatively thin-walled sleeve member extending substantially centrally with respect to said groove from the underface of said cap portion and terminating in a free end, said sleeve member being insertable into said bottle neck, and a substantially thin-walled skirt portion projecting from said cap portion at a location of the latter positioned at a level above the free end of said sleeve member, said skirt portion being substantially concentric with said sleeve member, extending beyond said annular groove and being engageable with a shoulder provided on the exterior of said bottle neck, whereby upon manipulation of said lug to swing said cap portion about said rimmed end of said bottle neck said skirt portion will be broken at said location and below said groove to thereby destroy said skirt portion without substantially making useless said cap portion.

Having thus described the invention, what is claimed as new and desired to be secured by Letters Patent, is:

A unitary closure device for a receptacle having a neck with a rim defining a mouth, comprising a cup-shaped cap portion having a side wall for covering and surrounding said rim of said neck and having a base for closing said mouth, said side wall adjacent the junction thereof with said base being thinner than at its edge remote from said base, a skirt portion having a main central section of substantially uniform wall thickness less than the thickness of said edge of said side wall, said skirt portion further having a first edge section of lesser wall thickness than said central section and a second edge section of greater wall thickness than said central section, said first edge section of said skirt portion being joined to said edge of said side wall and thus forming a prolongation of said side wall, said skirt portion being constructed to fit around said neck below said rim thereof and being provided with a plurality of substantially parallel longitudinal slots in said central section, said slots extending approximately from said first

edge section to said second edge section, whereby the flexibility and thus the neck-embracing characteristics of said skirt portion are materially enhanced, a substantially hollow cylindrical member protruding from said base of said cap portion and positioned interiorly of and concentrically with said side wall and said skirt portion, whereby an annular groove is defined between the outer surface of said cylindrical member on the one hand and the inner surface of said side wall and said skirt portion on the other hand, said groove being shaped to receive said rim of said receptacle upon positioning of said cap portion on said neck and upon insertion of said cylindrical member into said mouth, said cylindrical member extending from said base of said cap portion to a location beyond the junction between said edge of said side wall and said first edge section of said skirt portion, and a lug attached to and extending from the outer surface of said side wall at a location substantially adjacent said edge thereof, said lug being provided with a pressure surface essentially directed toward said second edge section of said skirt portion, whereby upon application of pressure against said pressure surface of said lug and in a direction toward said base said first edge section of said skirt portion will be ruptured to enable said cap portion together with said cylindrical member to be severed from said skirt portion and removed from said receptacle and retained for reuse with the latter without said skirt portion.
